PROCESS AND APPARATUS FOR
REFRIGERATION

James C. Armor, Bellevue, Pa.

Application September 28, 1932, Serial No. 635,147

14 Claims. (Cl. 62—5)

My invention relates to refrigeration by the absorption or adsorption principle and hereinafter for the sake of brevity I use the word "absorb" and its derivatives as including the word "adsorb" and its derivatives.

In the practice of my invention I alternately cool the absorbent to cause it to take up the refrigerant and heat the absorbent to distill the refrigerant therefrom.

10 I also preferably employ the principle that certain liquids, such, for instance, as brine and oil are poor conductors of heat so that a portion of a body of liquid such as the upper portion may be heated without materially raising the temperature of the lower portion of said body of liquid. This characteristic is especially marked where the body of liquid comprises a stratum of lighter liquid, such as oil, superimposed on a heavier liquid, such as brine.

20 In my invention I employ a container for the absorbent connected as by a tube with a second container into which the refrigerant is driven by distillation and wherein it condenses. When the predetermined quantity of refrigerant has been distilled from the absorbent-container and condensed in the condenser evaporator-container, the latter is brought into heat transfer relation with the subject to be refrigerated, such, for instance, as a refrigerating medium such as brine, the refrigerating medium cooling the latter and evaporating the previously condensed refrigerant, which evaporation causes the refrigerant to pass into and to be reabsorbed in the absorbent container. When the predetermined amount of refrigerant is evaporated and reabsorbed in the first container, the evaporator-container is now moved out of such heat transfer relation and concurrently the absorbent-container is brought into heating relation to a source of heat, such, for instance, as a gas flame. The heat now applied to the absorbent-container results in the distillation of the refrigerant out of the absorbent-container and its condensation in the condenser evaporator-container and the cycle of operation is thus continued.

I preferably arrange the two containers for movement in unison and by taking advantage of the shifting of the weight from one container to the other as the refrigerant is alternately absorbed into the one container and then distilled into and condensed in the other container, I am enabled to provide for the automatic movement of the containers and consequently the automatic operation of the process and apparatus. Thus I may mount the permanently connected containers on opposite sides of the axis of movement either of oscillation or rotation, in such a manner that the heavier or refrigerant-containing container will descend, overbalancing the lighter container and causing the latter to ascend. To obtain the

proper movement I prefer to position the axis of movement of the assemblage below its center of gravity, so that a shift of movement will be rapidly effected.

Other novel and characteristic features both of operation and apparatus will appear from the following description.

In the accompanying drawings, wherein I have illustrated a practical embodiment of the principles of my invention, Fig. 1 is a view partly in side elevation and partly in section showing a single unit apparatus.

Fig. 2 is a plan view of the same, the refrigerator being omitted.

Fig. 3 is a sectional detail on enlarged scale showing the combined fuel valve and center of rotation.

Fig. 4 is a fragmental view partially in section showing a modified form of fuel-valve arrangement.

Fig. 5 is a plan view partly in horizontal section showing a modification of the structure shown in Fig. 1.

Fig. 6 is a side elevation of the same.

Fig. 7 is a plan view of a two unit apparatus.

Fig. 8 is a side elevation of the same with parts in section.

Fig. 9 is a diagrammatic view in perspective showing another modified form of apparatus.

Fig. 10 is a sectional view of the same taken along the line 10—10 in Fig. 9.

Referring first to Figs. 1, 2, and 3 of the drawings, 1 represents a closed container which is the absorbent container. 2 represents a metal tube on one end of which the container 1 is mounted, the bore of the tube communicating with the interior of the container. On the other end of the tube 2 is mounted a second container 3 which is a condenser-evaporator and whose interior also communicates with the bore of the tube 2.

In this embodiment of my apparatus the tube 2 mechanically supports the containers 1 and 3, and is bowed or curved upwardly.

In the container 1 is a body of suitable absorbent material, such as calcium chloride, silver chloride, charcoal, &c., and the assemblage of containers 1 and 3 and tube 2 is provided with a suitable refrigerant, preferably ammonia.

4 represents a supporting arm whose upper end is fixed to the tube 2 at approximately the load-center of the latter. The lower end of the arm 4 is provided with a hub 5 which is rotatably mounted on an annular surface of the body 6 of a horizontally disposed fuel-valve. The hub 5 is provided with a lug 7 having a squared opening which fits over the squared end of the valve plug 8 so that as the arm 4 swings on the valve body as an axis the valve plug turns with the movement of the arm and opens and closes the valve.

9 represents a fuel-supply pipe leading to a burner 10, the valve 6—7 being interposed in said pipe so that the supply of fuel is alternately turned on and off as the unit comprising the two containers 1 and 3, the tube 2 and the arm 4 swings on its axis, the arrangement being such that as the unit moves counterclockwise into the position indicated by full lines in Fig. 1 and approaches the end of its movement, the valve 10 is opened and fuel is supplied to the burner, and as the unit starts a reverse or clockwise movement toward the position indicated in dotted lines in Fig. 1, the valve is closed.

The preferable fuel is natural or artificial gas, but oil or other suitable fuel may be employed. If desired an electric heater may be substituted for the heater 10 and the movement of the unit employed to open and close its circuit.

11 represents a valve which is used to shut off the fuel from pipe 9 or to regulate the supply therein. 12 represents a pilot light for the burner 10, said light constantly burning so as to ignite the burner when the fuel is admitted thereto.

13 is a vertically disposed flue provided with a heat-insulated wall and into the lower end of which the burner 10 projects. The container 1 also moves vertically in said flue, alternately descending into proximity to the burner and ascending away from the latter.

14 represents a tank and 15 a well forming the lower portion of the tank. The walls of the well are provided with heat-insulation, as indicated at 16 in Fig. 1. 17 represents a descending pipe connected to the bottom of the well 15 and connected at its other end with the cooling coil 18 contained in the refrigerator 19 or other compartment or space to be refrigerated. The other end of the coil 18 is connected by the return pipe 20 with the upper portion of the well 15. Thus a circulation of brine is provided for.

It is obvious that where the refrigeration is accomplished by the direct expansion system instead of by means of the indirect evaporating system, such as by the circulation of brine, the condenser-evaporator may be introduced directly into the space or compartment to be refrigerated instead of immersed in the brine or other fluid refrigerating medium.

The well 15, the pipes 17 and 20 and the coil 18 are filled with a suitable liquid refrigerating medium, such, for instance, as brine, while above the liquid the tank 14 is filled or partially filled with a liquid of less specific gravity, such as oil. If desired the brine may also partially fill the tank and the oil may be omitted, but I prefer to employ both liquids.

The arrangement is such that when the unit 1—2—3 is moved clockwise into the position indicated in dotted lines in Fig. 1, the container 3 is lowered into the well 15 and is immersed in the brine, but when the unit occupies the position indicated in full lines in Fig. 1 the container is elevated into the tank and is immersed in the oil.

65 The operation of the apparatus described is as follows:—

Assuming that the pilot light 12 is lighted but the valve 11 closed, the apparatus will be at room temperature and substantially all of the refrigerant will be absorbed in the container 1 except a small amount of vapor contained in tube 2 and container 3. The weight of the refrigerant is thus concentrated in the absorbent container 1 and thus the unit 1—2—3 will be in the position shown in solid lines in Fig. 1 with the container

1 lowered in the flue 13 into proximity with the burner 10 and the condenser-evaporator container 3 elevated into the stratum of oil in the tank 14. Thus the valve 6—8 is open for the passage of fuel to the burner 10. If the valve 11 be now opened, 5 the burner 10 will be lighted and the container 1 will be heated, thus distilling the refrigerant from the absorbent and driving it off through the tube 2 into the container 3 wherein it condenses. As the refrigerant is driven off from the container 10 1 into the container 3, the weight is shifted, thus causing the unit 1—2—3 to swing clockwise in Fig. 1, thereby elevating the container 1, closing the valve 6—8 and extinguishing the burner, and also causing the container 3 to descend into the well 15 and to be immersed in the brine.

The result is that the absorbent in container 1 cools while the previously condensed refrigerant in the container 3 by cooling the brine is evaporated, thus causing the refrigerant to travel 20 through the tube 2 back into the container 1 where it is reabsorbed.

Therefore the weight is shifted back to the container 1 causing the assemblage to swing counter-clockwise, causing the absorbent container 1 to descend into proximity to the burner, elevating the condenser-evaporator-container 3 out of the brine in well 15 and into the oil in tank 14. As the movement of the unit approaches its limit the valve 6—8 is opened and the burner 30 10 ignited, so that the refrigerant is again distilled out of the container 1 and the apparatus again reversed as above described.

21 represents a valve in the pipe 9 which is controlled by the thermostatic device 22 operated by 35 the internal temperature of the refrigerator 19, so that the supply of gas in the pipe 9 for the burner 10 will be regulated by the desired temperature within the refrigerator. As a substitute for the thermostatic control 21—22, a valve 40 23 indicated in dotted lines in Fig. 1 may be interposed in the brine circulating pipe 17 and controlled by the thermostatic mechanism 24 from the refrigerator 19.

Either of these forms of thermostatic control 45 may be used, but both are not necessary.

To prevent the escape or waste of oil or other liquid from the tank 14 I may provide the same with a lid 25 as indicated in Fig. 1 having an opening 26 of proper size to provide clearance for the 50 movement of the tube 2.

It is obvious that the apparatus is automatic, the refrigerant being alternately absorbed in container 1 and then distilled therefrom by the application of heat and condensed in container 3, 55 whence it is evaporated by the heat of the brine in the circulating system and reabsorbed in container 1.

In Fig. 4 I have shown the arm 4 mounted for movement on a shaft 27 instead of on the valve 60 body 6. The fuel pipe 9 is provided with a spring-closed valve 28 connected by a chain 29 with a lever 30 moving with the arm 4. As the arm swings counterclockwise and approaches the end of its path of movement the slack of the chain 65 is taken up and the valve opened to supply fuel to the burner. When the arm 4 starts a clockwise movement the chain slacks and the valve closes, to remain closed until the absorbent container is again lowered into its position for heat- 70 ing.

For the sake of illustration I have shown the containers as spherical, but it will be understood that their shape, dimension and relative sizes may be varied, as found convenient. 75

In Figs. 5 and 6 I illustrate a modification in which the tank 14 is entirely enclosed. Thus the tank is provided with a lateral extension 31 and both tank and extension are provided with a tight top-closure 32. The side wall of the extension 31 is provided with an opening in which is fixed the casing 33 of the fuel valve. The plug 34 of the valve has the arm 35 rigidly attached to its outer end and the arm 36 attached to its inner end. The container 1 is mounted on the outer end of the arm 35 and the container 3 is mounted on the outer end of the arm 36. The tube 2 which connects the containers 1 and 3 is led through an axial bore in the plug 34. Thus the arm 36 and the container 3 are sealed in the tank.

Thus far I have described a single unit apparatus, but it will be understood that any number of units, each comprising an absorbent container, a condenser-evaporator-container and connecting tube, may be employed in one apparatus, and the said units may be arranged either for independent movement or they may be coupled together to coact in their operation, the refrigerant in one unit or group of units being absorbed in the container or containers 1, while the refrigerant in the other unit or group of units is being condensed in the container or containers 3, thus maintaining a continuous cooling effect on the brine in the circulating system.

Thus in Figs. 7 and 8 I have illustrated two units, one comprised of the absorbent container 1a, the tube 2a, the condenser-evaporator-container 3a and the supporting arm 4a, while the other unit comprises the container 1b, the tube 2b, the container 3b and the arm 4b.

Each absorbent container is provided with its individual flue indicated at 13a and 13b. The gas burner 10 burns continuously and is positioned beneath a movable deflector-flue 37 whose upper end may be swung into registration with the lower end of either the flue 13a or 13b.

The arms 4a and 4b are provided with hubs 38 rotatably mounted on a shaft 39 carried by stands 40 rising from a support 41 upon which the flues and the tank may also be mounted. Each of the hubs 38 are provided with bevelled gears 42 facing each other and meshing with a third bevelled gear 43 fixed on the upper end of a vertically disposed shaft 44 journaled in the support 41. The lower end of the shaft 44 is attached to the deflector-flue 37 so that the latter is swung on a vertical axis by the movement of said shaft.

The tank 14 and well 15 are of such size and shape to receive both of the condenser-evaporator-containers 3a and 3b.

The parts are assembled so that one of the absorbent containers is lowered in its flue and the corresponding condenser-evaporator-container is elevated in the well 15, while the other absorbent container is elevated and the corresponding condenser-evaporator-container is lowered into the well. Thus in one of the units, 1a, 2a, 3a, 4a, the refrigerant is being distilled from the container 1a and condensed in the container 3a, while in the other unit 1b, 2b, 3b, 4b, the refrigerant is being evaporated from the container 3b and absorbed in the container 1b.

The deflector is swung into position under the flue 13a of the unit in which the refrigerant is being distilled.

It is evident that as the weight in the one unit shifts from container 1a to the container 3a and in the other unit from the container 3b

to the container 1b, the first unit will swing clockwise and the second unit will swing counterclockwise, reversing their relative position shown in Fig. 8, the deflector flue 37 being simultaneously shifted from the flue 13a to the flue 13b. Furthermore the units will reverse their positions when the refrigerant is again absorbed in the container 1a and distilled from the container 1b.

Thus the working of the apparatus is automatic and the brine is chilled by the alternate immersion of the condenser-evaporator containers therein.

In Figs. 9 and 10 of the drawings I illustrate another embodiment of the principles of my invention in a multiple unit refrigerating apparatus.

Thus a plurality of absorbent containers indicated at 1c, 1d, 1e, and 1f are symmetrically arranged about a common axis of rotation and are each connected by an individual tube, indicated at 2c, 2d, 2e, and 2f with their corresponding condenser-evaporator-containers 3c, 3d, 3e, and 3f. The tubes have intermediate straight portions which are inclosed and fixed in the tubular shaft 45 which is preferably disposed in an inclined position, such as shown in Fig. 9, and which is supported to rotate freely as by the bearings 46.

One end of the shaft, the upper one in Fig. 9, is mounted on a star-shaped shield 47 which is hollow and between whose radially disposed arms the absorbent containers are positioned, the containers being mounted on the short angularly bent ends of the corresponding tubes which protrude from the shield. At the other end of the shaft the tubes are provided with bent ends which extend through the wall of the tubular casing and have mounted thereon the corresponding condenser-evaporator-containers, the opposite bent ends of a tube being disposed in planes at right angles to each other, so that when an absorbent-container is being heated to distill the refrigerant therefrom the corresponding condenser-evaporator-container is raised out of the brine well and into the oil in the tank to receive and condense the refrigerant therein, while the absorbent-container, corresponding to the condenser-evaporator-container which is immersed in the brine in the well and thus having the refrigerant evaporated therefrom, is rotated away from the heating station so that it may cool and reabsorb the refrigerant.

The shaft 45 extends through the wall of the tank 14 at such an angle that the several condenser-evaporator-containers are in turn, as the shaft rotates, immersed and moved through the brine in well 15 to chill the brine and evaporate the refrigerant and then raised and moved through the oil in the tank 14 to permit the condensation of the refrigerant from the corresponding absorbent container.

48 represents a flue at whose lower end is placed the gas burner 10 which preferably burns continuously while the apparatus is in operation.

The flue 48 is apertured on its side as at 49 and the shield 47 is so disposed that as the shield rotates the absorbent containers are in turn brought into the flue and exposed to the gas flame, while the radial arms of the shield act to close the aperture 49 in the side of the shield and thus prevent the lateral escape of the heat from the flue. Thus in turn the absorbent containers are heated, to distill their contents into the corresponding condenser-evaporator-con-

tainers, and are cooled to permit the refrigerant evaporated from the corresponding condenser-evaporator containers to reabsorb.

Assuming the direction of rotation to be as indicated by arrows in Fig. 9, the refrigerant is being distilled from absorbent containers *1c* and *1d* into and condensed in condenser-evaporator-containers *3c* and *3d*, while the refrigerant is being evaporated from condenser-evaporator-containers *3e* and *3f* into absorbent-containers *1e* and *1f*, respectively, thus by progressively shifting the load causing the desired rotative movement to make the operation automatic.

50 represents means for applying rotative power to the apparatus, such as a bevelled gear mounted on the shaft and driven by a convenient power means where the operation is not to be wholly or in part automatic.

Among the advantages of my invention are the following.

It provides a means of automatically obtaining a refrigerating effect from gas or other fuel without water-cooling.

The construction is very simple, inexpensive and durable with few moving parts.

The moving parts operate only intermittently with comparatively very long intervals of rest. For that reason the machine will operate for many years without attention.

Again, all moving parts may be easily inspected and if trouble should develop it is easily detected and remedied.

There are no valves or obstructions of any description between the absorbent container and the condenser-evaporator, and for that reason no trouble can occur due to leaky or stuck valves, and the efficiency of the device remains constant throughout its entire long life.

The valves, check valves, float valves, expansion valves, &c. are weak points in other refrigerating machines, and are responsible for a considerable proportion of troubles which develop. The entire absence of these in my invention is one of its greatest advantages.

45 I claim:—

1. In a refrigerating apparatus operated on the absorption system, the combination of an absorbent container in which a refrigerant is absorbed when the container is unheated and from which the refrigerant is distilled when the container is heated, a condenser-evaporator container in which the distilled refrigerant is received and condensed and from which the refrigerant is evaporated by heat-transfer from the subject to be refrigerated, a bath comprising superimposed strata of liquids having different specific gravities in which the condenser-evaporator is to be immersed, and means for alternately simultaneously applying heat to the absorbent container and moving the condenser-evaporator container into the lighter liquid and simultaneously cutting off the heat from the absorbent container and moving the condenser-evaporator container into the heavier liquid.

65 2. In a refrigerating apparatus operated on the absorption principle, the combination of a plurality of absorbent containers, a like number of condenser-evaporator containers, tubes supporting and connecting said absorbent containers and condenser-evaporator containers in pairs, said tubes being mounted intermediate of their ends to rock on a horizontal axis and arranged to rock in unison in opposite directions, means for heating the absorbent containers when in the lowered positions, and heat-transfer means for evaporating the refrigerant from the condenser-evaporator containers when in their lower positions, the tubes and containers being moved by the travel of the refrigerant from one of the communicating containers to the other.

5 3. In a refrigerating apparatus operated on the absorption principle, the combination of a plurality of absorbent containers, a like number of condenser-evaporator containers, tubes supporting and connecting said absorbent containers and condenser-evaporator containers in pairs, said tubes being mounted intermediate of their ends to rock on a horizontal axis and arranged to rock in unison but in opposite directions, means for applying heat in turn to the absorbent containers as they move into their lower position, means whereby said heating means is actuated by the movement of the containers, and heat-transfer means for evaporating the refrigerant from the condenser-evaporator containers when in their lower positions, the tubes and containers being moved by the travel of the refrigerant from one of the communicating containers to the other.

10 3. In a refrigerating apparatus operated on the absorption principle, the combination of a plurality of absorbent containers, a like number of condenser-evaporator containers, tubes supporting and connecting said absorbent containers and condenser-evaporator containers in pairs, said tubes being mounted intermediate of their ends to rock on a horizontal axis and arranged to rock in unison but in opposite directions, means for applying heat in turn to the absorbent containers as they move into their lower position, means whereby said heating means is actuated by the movement of the containers, and heat-transfer means for evaporating the refrigerant from the condenser-evaporator containers when in their lower positions, the tubes and containers being moved by the travel of the refrigerant from one of the communicating containers to the other.

15 4. In a refrigerating apparatus operated on the absorption principle, the combination of a plurality of absorbent containers, a like number of condenser-evaporator containers, tubes supporting and connecting said absorbent containers and condenser-evaporator containers in pairs, said tubes being mounted intermediate of their ends to rock on a horizontal axis and arranged to rock in unison but in opposite directions, means for applying heat in turn to the absorbent containers as they move into their lower position, and heat-transfer means for evaporating the refrigerant from the condenser-evaporator containers when in their lower positions, the tubes and containers being moved by the travel of the refrigerant from one of the communicating containers to the other.

20 4. In a refrigerating apparatus operated on the absorption principle, the combination of a plurality of absorbent containers, a like number of condenser-evaporator containers, tubes supporting and connecting said absorbent containers and condenser-evaporator containers in pairs, said tubes being mounted intermediate of their ends to rock on a horizontal axis and arranged to rock in unison but in opposite directions, means for applying heat in turn to the absorbent containers as they move into their lower position, and heat-transfer means for evaporating the refrigerant from the condenser-evaporator containers when in their lower positions, the tubes and containers being moved by the travel of the refrigerant from one of the communicating containers to the other.

25 5. In a refrigerating apparatus operated on the absorption principle, the combination of a plurality of absorbent containers, a like number of condenser-evaporator containers, tubes supporting and connecting said absorbent containers and condenser-evaporator containers in pairs, said tubes being mounted intermediate of their ends to rock on a horizontal axis and arranged to rock in unison in opposite directions, means for heating the absorbent containers when in the lowered positions, and heat-transfer means for evaporating the refrigerant from the condenser-evaporator containers when in their lower positions, the tubes and containers being moved by the travel of the refrigerant from one of the communicating containers to the other, the axis of movement of said containers being disposed below the center of gravity whereby to accelerate the shift of said containers.

30 6. In a refrigerating apparatus operated on the absorption principle, the combination of a hollow shaft journaled for rotation on an axis angular to the horizontal, a plurality of absorbent containers mounted in annular series about one end of the shaft and rotating therewith, a similar number of condenser-evaporator containers mounted in annular series about the other end of the shaft and rotating therewith, tubes extending within the shaft and connecting each of said absorbent containers to one of the condenser-evaporator containers and the members of a connected pair of containers being relatively arranged about the shaft so that the alternate distillation of the refrigerant from an absorbent container and its condensation in the correspond-

ing condenser-evaporator container and the subsequent evaporation of the refrigerant from said condenser-evaporator container and its absorption in the corresponding absorbent container will cause said shaft to rotate, heating means arranged to be brought into heating relation with each of said absorbent containers in turn by the rotation of said shaft, and a bath comprised of two strata of liquids in which the 10 condenser-evaporator containers are immersed, the lower stratum being comprised of a liquid having greater specific gravity and in which said containers are in turn immersed after the refrigerant has been condensed therein and the 15 higher stratum of less specific gravity in which said containers are in turn immersed for the condensing operation.

7. In a refrigerating apparatus operated on the absorption principle, the combination of a hollow 20 shaft journaled for rotation on an axis angular to the vertical, a plurality of absorbent containers mounted in annular series about one end of the shaft and rotating therewith, a similar number of condenser-evaporator containers mounted in 25 annular series about the other end of the shaft and rotating therewith, tubes extending within the shaft and connecting each of said absorbent containers to one of the condenser-evaporator containers and the members of a connected pair 30 of containers being relatively arranged about the shaft so that the alternate distillation of the refrigerant from an absorbent container and its condensation in the corresponding condenser-evaporator container and the subsequent evapo- 35 ration of the refrigerant from said condenser-evaporator container and its absorption in the corresponding absorbent container will cause said shaft to rotate, heating means arranged to be brought into heating relation with each of said 40 absorbent containers in turn by the rotation of said shaft, and a bath comprised of two strata of liquids in which the condenser-evaporator containers are immersed, the lower stratum being comprised of a liquid forming part of the 45 circulating system and having greater specific gravity and in which said containers are in turn immersed after the refrigerant has been condensed therein and the higher stratum of less specific gravity in which said containers are in turn im- 50 mersed for the condensing operation.

8. In a refrigerating apparatus operated on the absorption system, the combination of a condenser-evaporator container in which a refrigerant is alternately condensed and from 55 which it is evaporated, a tank in which the container is moved from one portion of the tank to another portion thereof, a bath of liquid in said tank comprising a lower stratum of higher specific gravity and an upper stratum of lower 60 specific gravity, and means to immerse said container in the lower stratum for the evaporating operation and in the upper stratum for the condensing operation.

9. In a refrigerating apparatus operated on 65 the absorption system, the combination of a condenser-evaporator container in which a refrigerant is alternately condensed and from which it is evaporated, a tank in which the container is moved from one portion of the tank to another 70 portion thereof, a bath of liquid in said tank com-

prising a lower stratum of higher specific gravity and an upper stratum of lower specific gravity and means to immerse said container in the lower stratum for the evaporating operation and in the upper stratum for the condensing operation, 5 said container having insulated walls to prevent heat transference between the lower stratum of liquid and atmosphere.

10. The process of refrigerating a body of circulating liquid refrigerating medium, such for 10 instance as brine, which comprises the alternately repeated steps of condensing an inclosed body of a suitable refrigerant while immersed in a bath of liquid of less specific gravity than said liquid medium and then evaporating said 15 refrigerant by immersing the same in a portion of said circulating medium whereby the latter is chilled by heat-transference to said refrigerant.

11. In refrigerating apparatus, the combination of a condenser-evaporator container, a liquid bath composed of superimposed strata of liquids, the upper liquid of the upper stratum being of less specific gravity than that of the lower stratum and the latter being composed of a refrigerating medium such for instance as 20 brine, and means for moving said container into said upper stratum for the condensing operation and into the lower stratum for the evaporating operation.

12. In refrigerating apparatus operated on the 30 absorption system, the combination of an absorbent container in which the refrigerant is absorbed when the container is unheated and from which the refrigerant is distilled when the container is heated, a condenser-evaporator container 35 in which the distilled refrigerant is received and condensed and from which the refrigerant is evaporated by heat-transfer from the subject to be refrigerated, a bath comprising superimposed strata of liquids having different 40 specific gravities in which the condenser-evaporator container is immersed, and means for 45 moving the condenser-evaporator container into the stratum of less specific gravity to condense the refrigerant and into the stratum of greater specific gravity to evaporate the refrigerant.

13. In refrigerating apparatus, the combination of a condenser-evaporator container, a tank having its lower portion formed to contain a bath of liquid refrigerating medium such for instance 50 as brine, and the upper portion of the tank arranged to contain a bath of liquid of less specific gravity, and the containers being moved into the first mentioned liquid when it is desired to cool said liquid and into the second named liquid 55 when it is desired to cool the containers.

14. In refrigerating apparatus, the combination of a condenser-evaporator container, a tank having its lower portion formed to contain a bath of liquid refrigerating medium such for 60 instance as brine, and the upper portion of the tank arranged to contain a bath of liquid of less specific gravity, the containers being moved into the first mentioned liquid when it is desired to cool said liquid and into the second named liquid 65 when it is desired to cool the containers, and means for insulating the walls of the lower portion of said tank against heat-transference to atmosphere.
